[57] CLAIM

The ornamental design for a motorcycle mirror stem, as shown and described.

DESCRIPTION

FIG. 1 is a perspective front view of the motorcycle mirror stem.

FIG. 2 is an enlarged top view of the motorcycle mirror stem.

FIG. 3 is an enlarged front view of the motorcycle mirror stem.

FIG. 4 is an enlarged left side view of the motorcycle mirror stem.

FIG. 5 is an enlarged back view of the motorcycle mirror stem.

FIG. 6 is an enlarged right side view of the motorcycle mirror stem; and,

FIG. 7 is an enlarged bottom view of the motorcycle mirror stem.

The appearance of a second embodiment, for a left side motorcycle mirror stem, is understood to be a mirror image of the embodiment shown in FIGS. 1-7.

The dash lines depict environment and are not part of the claimed design.
